ATTORNEY

UNITED STATES PATENT OFFICE.

PETER ANDERSON, OF CHICAGO, ILLINOIS.

TOOL.

Application filed October 8, 1923. Serial No. 667,417.

To all whom it may concern:

Be it known that I, PETER ANDERSON, a subject of the King of Sweden, residing at Chicago, in the county of Cook and State 5 of Illinois, have invented certain new and useful Improvements in Tools, of which the following is a specification.

This invention relates to improvements in tools. The tool is adapted primarily for 10 taking lineal measurements although it is capable of other uses. More specifically the tool consists in the combination and arrangement of parts to be hereinafter fully described, pointed out in the appended 15 claims, and illustrated in the accompanying drawing which forms a part of this application and in which—

Fig. 1 is a view of the tool in side elevation;

20 Fig. 2 is a section taken on line 2—2 of Fig. 1;

Fig. 3 is a fragmentary view of Fig. 1, with a relatively adjustable element in an altered position;

25 Figs. 4 and 5 are, respectively, plan and side views of the relatively adjustable element; and

Fig. 6 is a cross-section taken on line 6—6 of Fig. 1.

30 Like reference characters denote corresponding parts throughout the several views.

The tool comprises a handle 1 which at 35 one end may be provided with the hammer head 2. The handle 1 is formed with a longitudinally extending groove 3 running from one end of the handle a distance somewhat in excess of one-half the length of the handle, the lateral edges of said groove 40 being covered by the co-extensive spaced lips 4, 5; said lips being spaced away from each other and above the bed of the groove.

A strip of wood or other material 6, preferably six inches in length, is fastened securely, by fastening means 7, in a longitudinally trough-shaped, slotted, spring-metal strip 8, the slot 9 in said metal strip being of the same extent as the wood strip, said metal strip extending substantially beyond 50 the wood strip and terminating in the oppositely disposed ears 10. The metal strip is fastened to the lateral edges of the wood strip, the sides of the metal strip being connected by the integral bridge 11 at one end and the opposite end of said strip, beyond

the wood strip, merging into the straight flat neck portion 12 that terminates in the said ears 10.

The width of the metal strip is such that it fits snugly between the lips 4, 5 in the handle, and the thickness of the wood strip is such that it rides upon the base of the groove 3 in the handle, with its upper face flush with the upper surface of the said lips, as clearly shown in Fig. 6. The metal strip is introduced into the groove 3 at the open end of the same, the ears 10 riding in the groove 3 beneath the lips 4, 5. It will be noted that the lips 4, 5 hold the ears 10 in such position that the neck 12 of the metal strip is bent toward the base of the groove 3, as shown in Fig. 2, when the said strip is disposed in said groove, the opposite end of said strip being prevented from rising out of the groove by the bridge 13 that spans the metal strip and is secured to the handle 1 upon opposite sides of its groove 3. To move the metal and wood strips into the position shown in Fig. 3, at right angles to the handle 1, said strips are forced forward in the groove 3 until the end of the metal strip passes from beneath the bridge 13, when the tension of the neck 12 will cause the strip to assume the position shown in Fig. 3. The strip 8 is graduated in inches as shown, as is also the wood strip 6, and, holding the tool by the head 2, the strip 8 may be used as a rule to take measurements or, in connection with the handle 1, as a carpenter's square. 90

What is claimed is:—

1. In a tool, a handle formed with a longitudinal groove open at one end, a bridge across the groove at one end of said handle, a spring-metal strip, trough-shaped throughout the greater portion of its length, adapted to slide in said groove beneath said bridge, said strip being of lesser length than said groove, and ears formed terminally of said strip for sliding engagement with the said handle whereby said strip may be yieldingly forced out of said handle groove. 95

2. In a tool, a handle formed with a longitudinal groove open at one end, lips integral with said handle and extending over the lateral edges of said groove, a bridge across the groove at one end of said handle, a spring-metal strip, trough-shaped throughout the greater portion of its length but terminating at one end in a flat 100 105 110

neck portion in yielding alinement with the
base of said trough, said metal strip being
adapted, in inverted position, to slide in
said groove beneath said bridge, said strip
5 being of lesser length than said groove, a
wood strip carried by said metal strip, and
ears formed terminally of the neck of said

strip for disposal in said groove beneath
said lips.

In testimony that I claim the foregoing 10
as my own I have hereto affixed my signa-
ture.

PETER ANDERSON.
